(57) **CLAIM**

The ornamental design for a container portion, as shown and described.

DESCRIPTION

FIG 1 is a perspective view showing my new design;
FIG 2 is a front elevational view thereof;
FIG 3 is a rear elevational view thereof;
FIG 4 is a left side elevational view thereof;
FIG 5 is a right side elevational view thereof;
FIG 6 is a top plan view thereof; and,
FIG 7 is a bottom plan view thereof.

The broken lines shown in the drawings are for environmental purposes only and form no part of the claimed design.
